WELL PLUGGING, PACKING, AND/OR
TESTING TOOL

George P. Maly and Edward A. Pullen, Fullerton, Calif.,
assignors to Union Oil Company of California, Los
Angeles, Calif., a corporation of California

Filed Nov. 19, 1957, Ser. No. 697,350

19 Claims. (Cl. 166—187)

This invention relates to a well tool, and in particular concerns a device adapted to be inserted in a well bore for the purpose of dividing the bore laterally into two or more portions. In accordance with the invention, the principle thereof is embodied in the form of simple plugging or packing tools, or in devices for sampling well fluids and/or determining their nature and the conditions under which they exist within the subterranean strata traversed by the well bore.

The use of packers or plugs in well bores in connection with such operations as cementing, repressuring, testing, etc., is well known, and a great variety of such tools has been proposed. All of such devices, however, comprise one or more sealing elements which are capable of being inserted into the well bore and expanded radially therein until they meet the walls of the bore or the well casing and engage the same in fluid-tight relationship. Such packing elements have been actuated by mechanical or hydraulic means controlled from the earth's surface.

It is an object of the present invention to provide a well tool comprising a sealing element which is actuated by pressure developed within the well bore. Another object is to provide a device of such character in which the actuating pressure is generated immediately adjacent the sealing element itself. A further object is to provide such a device in which the actuating pressure is that developed by a material when it undergoes a change in phase from the solid to the liquid state. Other and related objects will be apparent from the following detailed description of the invention, and various advantages not specifically referred to herein will be apparent to those skilled in the art upon employment of the invention in practice.

In the drawings which form a part of this application:

Figure 1 is a longitudinal sectional view of a simple embodiment of the invention illustrating the principle thereof.

Figure 2 is a longitudinal sectional view of the device of Figure 1 after expansion of the sealing element thereof.

Figure 3 is a longitudinal sectional view of another embodiment of the invention in which multiple sealing elements are provided.

Figure 4 is a longitudinal sectional view of a well tool embodying the principle of the invention and comprising a plurality of spaced sealing elements which serve to divide a selected length of a well bore into a plurality of isolated portions.

Figure 5 is a longitudinal sectional view of a modification of the device of Figure 4.

Figure 6 is a longitudinal sectional view of a well-fluid testing device embodying the principle of the invention.

Referring now to Figures 1 and 2, in which like numerals designate like parts, the device there shown is a packer for closing off the annulus between a well casing and tubing. Said packer consists of a mandrel or conduit 10 which constitutes the body portion of the device. Said body portion is provided with screw threads at its

2

upper end, whereby it may be attached to and made a part of the well tubing string. Upper and lower retaining plates 11 and 12, respectively, are rigidly affixed to conduit 10 in parallel spaced relationship, and have outside diameters smaller than the inside diameter of well casing 13 in which the device is to be employed. Annular sealing ring 14, normally having an outside diameter smaller than the inside diameter of well casing 13 and an inside diameter considerably larger than the outside diameter of conduit 10 but smaller than the outside diameter of plates 11 and 12, is held between plates 11 and 12 in sliding engagement with the opposed faces thereof. Sealing ring 14 is constructed of a resilient expansible material which is not attacked by the well fluids, and may suitably be a hydrocarbon-resistant synthetic rubber such as Thiokol or neoprene. By reason of the difference in the diameters of conduit 10, retaining plates 11 and 12, and sealing ring 14, the device comprises an enclosed annular chamber, the lateral surfaces of which are defined by the opposed faces of plates 11 and 12 and the longitudinal surfaces of which are defined by the outer surface of conduit 10 and the inner surface of sealing ring 14. Said annular chamber is substantially completely filled with a body 15a of a material which changes from a solid to a liquid with an increase in volume at a temperature between that of the atmosphere at the earth's surface and that which exists within the well bore at the point where the device is to be employed.

Operation of the device of Figures 1 and 2 is as follows: The assembly is coupled to the well tubing by means of the screw threads on conduit 10 and is lowered into the well casing to the desired level. Inasmuch as the body of a meltable material 15a has a melting point below that which exists at such level, upon the attainment of equilibrium temperature conditions body 15a will melt to form a body of liquid (15b in Figure 2) of increased volume. The force of the expansion is directed radially and outwardly against the inner surface of sealing ring 14, and the latter, being resilient and expansible, is thus forced outwardly against casing 13 to form a fluid-tight seal therewith as shown in Figure 2.

Referring now to Figure 3, the device there shown is a plugging tool which is similar in purpose and construction to that of Figures 1 and 2, except that two sealing rings are provided in order to cope with higher pressure differentials across the tool. Said device consists of a body member 20 having three retaining plates 21, 22 and 23 rigidly affixed thereto. Upper and lower sealing rings 24 and 25, respectively, are held between the opposed faces of retaining plates 21 and 22 and 22 and 23, respectively. Upper and lower bodies of meltable material 26 and 27, respectively, substantially fill the two annular closed spaces defined by the sealing rings, the retaining plates and the conduit. The operation of the device is exactly like that of the device of Figures 1 and 2.

We are aware that it has been proposed to construct packing and plugging tools in which a resilient sealing element is forced outwardly against the well casing by means of a fluid which is forced down the well tubing or other conduit under pressure. The devices of the present invention, however, operate under an entirely different principle in that the pressure which forces the sealing element outwardly against the well casing is developed, not by a pump at the earth's surface and transmitted to the device via a column of fluid, or even by the hydrostatic head of a column of liquid, but rather by a body of material undergoing the increase in volume which accompanies a change from the solid to the liquid state. The pressures generated during such change in state are known to be remarkably high, but insofar as we are aware they have not heretofore been employed for actu-

ating the sealing elements of a well packer or the like.

The meltable material employed in the devices of the invention is preferably a hydrocarbon wax, i.e., a solid paraffin, but may be any material which increases in volume upon changing from the solid to the liquid state. As previously stated, such change of state should occur at a temperature above that of the atmosphere at the well head but below that which prevails at the point within the well bore where the sealing element is to be actuated. Such temperature is ordinarily between about 75° F. and about 300° F. The hydrocarbon waxes are preferred by reason of their low cost, their inertness with respect to materials of construction and, in particular, by reason of the fact that they undergo a relatively large volume change upon melting and can be blended to have substantially any desired melting point within the stated temperature range. Since it is usually desirable that the wax have a fairly sharp melting point, relatively highly refined de-oiled waxes are especially preferred, particularly those which melt fairly sharply in the range 140°-200° F. The increase in volume upon melting is of importance in that it determines the dimensions of the device. Thus, in the device of Figure 1, if the body of meltable material 15a is of such nature that the increase in volume upon melting is, say, 5 percent, the outside diameter of sealing ring 14 will have to be more nearly equal to the inside diameter of casing 13 than if such volume increase is, say, 20 percent. However, this is because, in the latter instance, sealing ring 14 will be expanded a greater radial distance than because of any substantial difference in the pressure developed. As a practical matter, we prefer to employ a hydrocarbon wax which undergoes a volume increase of at least about 10 percent.

In addition to the preferred hydrocarbon waxes, the body of meltable material may also be composed of a metal or metal alloy having the appropriate melting point and also having the property of expanding on melting. Certain alloys of bismuth possess these properties. In addition, reference to any dictionary of chemical compounds, e.g., The Handbook of Chemistry and Physics, will disclose numerous organic compounds which fulfill the requirements, and any of such compounds may be employed.

Referring now to Figure 4, which illustrates another embodiment of the invention in the form of a simple well-fluid sampling tool, the device there shown comprises a conduit 40 provided with screw threads at its upper end, whereby it may be attached to the well tubing. Retaining plates 41-46 are rigidly affixed, as by welding, to conduit 40 in spaced pairs; plates 41 and 42 form an upper spaced pair, plates 43 and 44 form a middle spaced pair, and plates 45 and 46 form a lower spaced pair. Conduit 40 is provided with perforations 47a and 47b between adjacent spaced pairs of retaining plates. Sealing rings 48a, 48b, and 48c are held between each pair of retaining plates as previously described in connection with Figures 1-3, and each of the enclosed annular spaces defined by conduit 40 and each pair of retaining plates and each sealing ring is filled with a body 49a, 49b, and 49c of a normally solid material of suitable melting point, e.g., paraffin wax having a melting point between 140° and 160° F. The upper retaining plate of each pair, i.e., retaining plates 41, 43 and 45, is provided with a filler hole through which the bodies of paraffin wax 49a-49c are introduced during assembly of the device, said filler holes being normally closed by plugs 56a-56c. Cylindrical shells 50 and 51, provided with lateral perforations 53, extend between the opposed faces of adjacent pairs of retaining plates and engage the same in fluid-tight relationship. The dimensions of the device are such that it is normally capable of being inserted into well casing 54 which has been perforated as at 55.

In accordance with one method of employing the

sampling device of Figure 4, the tool is inserted into the well bore on the end of the tubing string, and is positioned within the bore so as to span the strata whose effluents are to be sampled. If the well is flowing, superimposed pressure may be applied to the casing to prevent well fluids from entering the same while the tool is being placed in position. Alternatively, an inert gas may be forced down the well tubing under sufficient pressure to prevent well fluids from entering the tool during its positioning. The tool is then "set" by holding it in place until the bodies of paraffin wax melt by reason of the ambient temperature being above their melting point. Such melting is accompanied by an increase in volume, and the pressure developed thereby is directed radially against the sealing rings, whereby the latter expand outwardly to form fluid-tight seals with the well casing. Once the tool has been "set" in this manner, the well is allowed to flow and the effluents from the strata spanned by each of the cylindrical shells 50 and 52 pass as individual streams, via perforations 55 in the well casing and perforations 53 in the shells, into each of the chambers enclosed by said shells. Perforations 47a-47b in conduit 40 allow the air or other gas which fills each chamber to be displaced therefrom as the well fluids enter perforations 53. When equilibrium conditions have been established, the tool is withdrawn from the well bore. The contents of each of the chambers are representative of the effluent from each of the strata spanned by each of said chambers. From the dimensions of the tool, i.e., the length of each of the cylindrical shells and the known depth at which the tool was positioned, the depth and thickness of the various strata investigated are known, and examination of the contents of each chamber provides information as to the nature and amount of the fluids effluent from each of said strata. As is apparent, the device may be constructed so as to have any number of chambers extending between adjacent sealing rings held between adjacent retaining plates constituting a pair.

The device of Figure 4 may also be employed as a plugging tool to inject a plugging agent into a particular stratum or strata traversed by the well bore. In accordance with such use, the device is employed as above described to determine the location of those strata from which undesirable well fluids, e.g., water, flow into the well bore. Those portions of the tool which were found to span a stratum or strata producing desired well fluids are then plugged off as by inserting plugs in perforations 47a and/or its counterparts. The tool is then reinserted in the well bore in its previous position, whereby only those portions of the tool which span the sources of undesirable fluids are placed in communication with conduit 40. A suitable plugging agent, e.g., cement or a liquid capable of forming a solid resin upon lapse of time, is pumped down conduit 40, through perforations 47a, 53 and 55, and into the strata wherein said agent solidifies to form a plug. The tool is then withdrawn from the bore, whereby only those strata which produce desirable well fluids are placed in communication with the bore.

Referring now to Figure 5, there is shown a modification of the sampling tool described above in connection with Figure 4. Those parts which the devices of Figures 4 and 5 have in common are designated by like numerals. The device comprises a central conduit 40 having retaining plates 41, 42, 43, 44, and 45 rigidly affixed thereto in spaced pairs. Sealing rings 48a, 48b and 48c are held between each pair of retaining plates, and each of the annular spaces formed by each pair of retaining plates and the sealing ring associated therewith is substantially filled with a body 49a, 49b and 49c of a material such as paraffin wax. The tool is shown positioned within well casing 54 in "set" condition, i.e., the bodies of wax 49a and 49b are shown in molten form with sealing rings 48a-48c expanded to form fluid-tight seals with casing 54. The latter is perforated as at 55.

Cylindrical shells 50a and 51a extend between adjacent pairs of retaining plates, thereby forming a series of closed chambers 57a and 57b. Within chamber 57a a conduit 58 communicates between the exterior of the tool and the interior of conduit 40, and a solenoid-operated valve 59 is interposed in conduit 58. Valve 59 is operated by an electric current supplied thereto from the earth's surface via an electrical conductor 60 which passes through the wall of conduit 40 via seal 64. By suitably operating valve 59 the well effluents which pass through perforations 55 can be diverted into chamber 57a through valve port 61. In employing the device of Figure 5 to obtain samples of the strata spanned by chamber 57a, the device is lowered into the well bore with valve 59 in closed position. When sealing rings 48a and 48b are set by the melting and accompanying expansion of the bodies of paraffin wax 49a and 49b, valve 59 is opened to allow said well fluids to enter chamber 57a via perforations 55, conduit 58, valve 59, and port 61. When equilibrium conditions are attained, valve 59 is closed and the tool is withdrawn from the well bore.

Figure 5 also shows a modification whereby the device may be employed to determine the in situ properties of well effluents. Such modification takes the form of instrument means 62 positioned in chamber 57b. Said instrument means are interposed in conduit 63 communicating between the exterior of the tool and conduit 40, and may comprise a flowmeter, a thermometer, a pressure gauge, or any other instrument suitable for determining the properties of the fluid which enters chamber 57b via conduit 63. Instrument means 62 may be of the self-recording type or it may be a telemetering device which transmits the information it detects to the earth's surface through an electrical conductor 65 which passes through the wall of conduit 40 via seal 66. Such devices are well known in the art.

In the preceding description of the operation of the devices of Figures 4 and 5 nothing was said concerning the manner in which the tool was removed from the well bore. In wells in which the effluents from the various strata flow into the bore under more or less the same pressure, the sealing rings need not engage the well casing with any great degree of force, and in such instance the "set" tool may be withdrawn from the bore simply by lifting it with sufficient force to overcome the relatively small frictional resistance between the sealing rings and the well casing. In other cases, a refrigerating fluid may be forced down the central conduit to freeze the bodies of paraffin wax, or other meltable material, thereby causing them to contract and allowing the resilient sealing rings to retract out of engagement with the well casing. Alternatively, the device itself may be so constructed as to be retractable. Such a form of device is shown in Figure 6.

Referring now to Figure 6, the device is shown positioned in a well bore prior to "setting" of the sealing elements. Said device comprises an upper conduit section 70, a middle conduit section 71, provided with perforations 72, and a lower conduit section 73. The latter, at its lower end, threadedly engages supporting plate 90 which rests on tool support 91 affixed to the inside of well casing 79. Upper conduit section 70 is attached to the lower end of well tubing string 74 by coupling 75. Each of said conduit sections is threadedly joined to the adjacent conduit section through a packing element assembly 76 or 76a. Each of the assemblies 76 and 76a consists of upper and lower disc-shaped jaws, 77, 77a, 78 and 78a, respectively, having outside diameters less than the inside diameter of perforated casing 79 in which the tool is positioned. Each jaw is provided with a threaded central opening 80 which receives and engages the end of one of the conduit sections as shown, and is further provided with an inwardly projecting shoulder 81 which extends part-way across the inner diameter of the particular conduit section which the jaw engages. The

adjacent faces of upper and lower jaws 77, 77a, 78 and 78a are hollowed out back from their peripheries so that when the jaws are placed with said faces adjoining an annular space exists between each pair of jaws. Resilient sealing rings 82 and 82a, having normal outside diameters less than the inside diameter of casing 79 and having inner diameters considerably greater than that of the aforesaid hollowed out portions of said jaws, are interposed between said jaws. A body 83a or 83b of solid material of suitable melting point fills the remainder of the hollowed-out space between each pair of jaws. Spool-shaped members 84a and 84b having upper and lower shoulder portions 85a, 85b, 86a and 86b, respectively, are positioned within the conduit in such manner that upper shoulder portions 85a and 86a overlap shoulder portions 81 of upper jaws 77 and 78, respectively, and lower shoulder portions 85b and 86b overlap shoulder portions 81 of lower jaws 77a and 78a, respectively. Spool-shaped members 84a and 84b are of such length that the upper and lower shoulder portions thereof are separated by a distance greater than the combined thickness of shoulder portions 81 of upper and lower jaws 77, 77a, 78 and 78a. When the device is lowered into the well bore the tool is somewhat loosely held together by spools 84a and 84b, i.e., middle conduit section will hang from spool 84a via the shoulder 81 of jaw 77a engaging shoulder 85b of spool 84a, and lower conduit section will hang from spool 84b via the shoulder of jaw 78a engaging shoulder 86b of spool 84b. Accordingly, jaws 77 and 77a and jaws 78 and 78a will be separated slightly and some lateral motion will be possible. However, by making sealing rings 82 and 82a only slightly smaller than the internal diameter of casing 79, such lateral motion is minimized, and the distance by which the jaws are separated can be kept at a minimum by suitable dimensioning of the spools. Should the bodies of meltable material be soluble in the well fluids, the well may be pumped dry or back pressure applied during lowering of the tool in the bore. Alternatively, sealing rings 82 and 82a may be made sufficiently resilient to fill the space between the pairs of jaws even though the jaws are separated to some extent. When the device is positioned within the casing, resting on tool support 91 as shown, the weight of tubing string 74 will maintain jaws 77 and 77a (and jaws 78 and 78a) tightly pressed together so that when bodies 83a and 83b of meltable material cannot exude between the respective jaws. When upper conduit section 70 and upper jaw 77 are raised, spool member 84a will likewise be raised by reason of its shoulder portion 85a engaging shoulder portion 81 of upper jaw 77, but lower jaw 77a will not be raised until its shoulder portion 81 is engaged by lower shoulder portion 85b of spool 84a. After the tool has been "set" within casing 79 as a result of bodies 83a and 83b of solid material melting, when a lifting force is placed on well tubing 74, the jaws 77 and 77a of upper packing element assembly 76 will be pulled apart, thereby creating a larger enclosed space for the body of molten material and allowing sealing ring 82 to contract. If such lifting force is continued, jaws 78 and 78a of lower packing element assembly 76a will similarly be pulled apart by engagement of spool 84b with shoulder portions 81 of jaw members 78 and 78a. This arrangement permits the tool to be removed from the well after it has been set and sealing rings 82 and 82a expanded against casing 79, and, furthermore, allows the seals to be broken one at a time.

The space between upper and lower packing element assemblies 76 and 76a and the exterior of middle conduit section 71 contains a body of a foraminous fluid-sensitive material 87 held in place by a screen or other foraminous retainer 88. Fluid-sensitive material 87 is of such nature that it undergoes an observable chemical or physical change upon being contacted with a particular well fluid. For example, it may comprise sawdust impregnated with a cobalt salt which changes color upon contact with water

or brine. When the tool is positioned in the well bore and the well is placed on production, the fluids produced by the strata opposite middle conduit section 71 will pass through fluid-sensitive material 87 and into conduit section 71 via perforations 72. Upon withdrawing the tool and examination of fluid-sensitive material 87, it can be determined from the color thereof whether such fluid is water or brine rather than oil. Fluid-sensitive material 87 may also be of such nature that it swells in contact with water, so that the tool serves as an automatic plugging or water-shutoff device. Fluid-sensitive material 87 may also be oil- or gas-sensitive in order to indicate or plug off such fluids.

In employing the device provided by the invention at relatively great depths, it may be necessary to provide means to prevent the bodies of meltable material from melting (and thus "setting" the sealing rings) before the tool has reached its desired point of use. Such means may suitably comprise thermal insulation applied to the exposed faces of the retaining plates. Alternatively, the temperature within the well bore may be temporarily lowered to a value below the melting point of the meltable material by circulating a refrigerant through the well bore prior to insertion of the tool.

As will be apparent to those skilled in the art, the principle of the present invention may be applied to a wide variety of packers, plugs and other tools, and the device of the invention may take many forms other than those illustrated and described therein. In its broadest aspect the device provided by the invention comprises an elongated body portion adapted to be lowered into a well bore, at least two spaced retaining members extending from the outer surface of the body member substantially perpendicular to the axis thereof, a continuous resilient expansible sealing ring held between adjacent retaining members adjacent the peripheries thereof, and a body of inert solid material which expands upon melting and which has a melting point between the atmospheric temperature at the earth's surface and the ambient temperature at the point within the well bore where the tool is to be positioned, said body of solid material being held between adjacent retaining members and occupying the space between the body portion and the sealing ring. The term "inert" is intended to limit the body of solid material to those materials which do not chemically attack the elements by which said bodies are contained.

Other modes of applying the principle of our invention may be employed instead of those explained, change being made as regards the elements or means employed provided the apparatus stated by any of the following claims, or the equivalent of such stated apparatus, be constructed or employed.

We, therefore, particularly point out and distinctly claim as our invention:

1. A well tool comprising an elongated body portion adapted to be lowered into a well bore; at least two spaced rigid retaining members affixed to said body portion and extending outwardly from the longitudinal axis thereof, the opposed faces of adjacent retaining members extending over a substantial portion of the cross-sectional area of the well bore; a continuous annular resilient expansible sealing element extending between the opposed faces of adjacent retaining members adjacent the peripheries thereof and surrounding said body portion at a distance therefrom; and a body of inert material substantially filling the annular space enclosed by adjacent retaining members and the sealing element associated therewith and said body member, said material being one having a melting point above the temperature of the atmosphere at the earth's surface but below that at the location within the well bore where the tool is to be employed and also being one which increases in volume upon melting.

2. A well tool as defined by claim 1 wherein said body of inert material consists of a hydrocarbon wax

which increases in volume to an extent of at least about 10 percent upon melting.

3. A well tool as defined by claim 1 wherein said body of inert material consists of a metal alloy.

4. A well tool comprising a hollow elongated conduit laterally perforated over a portion of its length and adapted to be lowered into a well bore on a well tubing string; an upper pair of spaced rigid retaining members affixed to said conduit above a perforated portion thereof and extending outwardly from said conduit in horizontal planes perpendicular to the longitudinal axis thereof, the opposed faces of the retaining members which constitute said upper pair being substantially circular and having diameters smaller than the inside diameter of said well bore; a lower pair of spaced rigid retaining members affixed to said conduit below a perforated portion thereof and extending outwardly from said conduit in horizontal planes perpendicular to the axis thereof, the opposed faces of the retaining members which constitute said lower pair being substantially circular and having diameters smaller than the inside diameter of said well bore; a continuous annular resilient expansible sealing ring extending between the opposed faces of the retaining members which constitute each of said pairs adjacent the peripheries thereof and surrounding said conduit at a distance therefrom; a body of inert material substantially filling the annular space enclosed between the retaining members which constitute each of said pairs and between each of said sealing elements and said conduit, said material being one having a melting point above the temperature of the atmosphere at the earth's surface but below that at the location within the well bore where the tool is to be employed and also being one which increases in volume upon melting; and a perforated tubular member extending between said upper and lower pairs of retaining members adjacent the peripheries thereof.

5. A well tool as defined by claim 4 wherein said body of inert material consists of a hydrocarbon wax which increases in volume to an extent of at least about 10 percent upon melting.

6. A well tool comprising a hollow elongated conduit laterally perforated over a portion of its length and adapted to be lowered into a well bore on a well tubing string; an upper pair of spaced rigid retaining members affixed to said conduit above a perforated portion thereof and extending outwardly from said conduit in horizontal planes perpendicular to the longitudinal axis thereof, the opposed faces of the retaining members which constitute said upper pair being substantially circular and having diameters smaller than the inside diameter of said well bore; a lower pair of spaced rigid retaining members affixed to said conduit below a perforated portion thereof and extending outwardly from said conduit in horizontal planes perpendicular to the axis thereof, the opposed faces of the retaining members which constitute said lower pair being substantially circular and having diameters smaller than the inside diameter of said well bore; a continuous annular resilient expansible sealing ring extending between the opposed faces of the retaining members which constitute each of said pairs adjacent the peripheries thereof and surrounding said conduit at a distance therefrom; a body of inert material substantially filling the annular space enclosed between the retaining members which constitute each of said pairs and between each of said sealing elements and said conduit, said material being one having a melting point above the temperature of the atmosphere at the earth's surface but below that at the location within the well bore where the tool is to be employed and also being one which increases in volume upon melting; and a body of a foraminous fluid-sensitive material extending between said upper and lower pairs of retaining members.

7. A well tool as defined by claim 6 wherein said body of inert material consists of a hydrocarbon wax which increases in volume to an extent of at least about 10 percent upon melting.

8. A well tool as defined by claim 6 wherein said foraminous fluid-sensitive material is a material which undergoes observable physical change upon being contacted with aqueous well effluents.

9. A well tool comprising a hollow elongated conduit laterally perforated over a portion of its length and adapted to be lowered into a well bore in a well tubing string; an upper pair of spaced rigid retaining members affixed to said conduit above a perforated portion thereof and extending outwardly from said conduit in horizontal planes perpendicular to the longitudinal axis thereof, the opposed faces of the retaining members which constitute said upper pair being substantially circular and having diameters smaller than the inside diameter of said well bore; a lower pair of spaced rigid retaining members affixed to said conduit below a perforated portion thereof and extending outwardly from said conduit in horizontal planes perpendicular to the axis thereof, the opposed faces of the retaining members which constitute said lower pair being substantially circular and having diameters smaller than the inside diameter of said well bore; a continuous annular resilient expansible sealing ring extending between the opposed faces of the retaining members which constitute each of said pairs adjacent the peripheries thereof and surrounding said conduit at a distance therefrom; a body of inert material substantially filling the annular space enclosed between the retaining members which constitute each of said pairs and between each of said sealing elements and said conduit, said material being one having a melting point above the temperature of the atmosphere at the earth's surface but below that at the location within the well bore where the tool is to be employed and also being one which increases in volume upon melting; and a body of a foraminous fluid-sensitive material disposed exterior of said conduit and extending across each of the perforations therein.

10. A well tool as defined by claim 9 wherein said body of inert material consists of a hydrocarbon wax which increases in volume to an extent of at least about 10 percent upon melting.

11. A well tool as defined by claim 9 wherein said foraminous fluid-sensitive material is a material which undergoes observable physical change upon being contacted with aqueous well effluents.

12. A well tool comprising a hollow elongated conduit laterally perforated over a portion of its length and adapted to be lowered into a well bore in a well tubing string; an upper pair of spaced rigid retaining members affixed to said conduit above a perforated portion thereof and extending outwardly from said conduit in horizontal planes perpendicular to the longitudinal axis thereof, the opposed faces of the retaining members which constitute said upper pair being substantially circular and having diameters smaller than the inside diameter of said well bore; a lower pair of spaced rigid retaining members affixed to said conduit below a perforated portion thereof and extending outwardly from said conduit in horizontal planes perpendicular to the axis thereof, the opposed faces of the retaining members which constitute said lower pair being substantially circular and having diameters smaller than the inside diameter of said well bore; a continuous annular resilient expansible sealing ring extending between the opposed faces of the retaining members which constitute each of said pairs adjacent the peripheries thereof and surrounding said conduit at a distance therefrom; a body of inert material substantially

filling the annular space enclosed between the retaining members which constitute each of said pairs and between each of said sealing elements and said conduit, said material being one having a melting point above the temperature of the atmosphere at the earth's surface but below that at the location within the well bore where the tool is to be employed and also being one which increases in volume upon melting; a tubular member extending between said upper and lower pairs of retaining members adjacent the peripheries thereof; and controllable valve means in register with a perforation in said tubular member for establishing and disestablishing communication between the exterior of the tool and the annular space between said tubular member and said conduit.

13. A well tool as defined by claim 12 wherein said body of inert material consists of a hydrocarbon wax which increases in volume to an extent of at least about 10 percent upon melting.

14. A well tool as defined by claim 13 wherein means for detecting physical conditions within the annular space between said tubular member and said conduit are positioned therein.

15. A well tool comprising an elongated body portion adapted to be lowered into a well bore on a well tubing string; a plurality of circular rigid retaining plates affixed to said conduit and extending outwardly therefrom in horizontal planes perpendicular to the longitudinal axis thereof, said retaining plates having diameters smaller than the inside diameter of said well bore and being affixed to said conduit in a configuration of a plurality of spaced pairs; a plurality of continuous annular inert resilient expansible sealing rings, each of which extends between the opposed faces of the retaining plates which constitute each of said pairs adjacent the peripheries thereof; a body of inert material substantially filling each of the annular spaces defined by said conduit and the opposed faces of the retaining plates which constitute each of said pairs and the sealing ring associated therewith, said inert material being one having a melting point above the temperature of the earth's surface but below that at the level it occupies within the well bore when the tool is in use and also being one which increases in volume upon melting; and a plurality of perforate tubular members each of which extends between adjacent pairs of said retaining plates adjacent the peripheries thereof.

16. A well tool as defined by claim 15 wherein said body of inert material consists of a hydrocarbon wax which increases in volume to an extent of at least about 10 percent upon melting.

17. A well tool as defined by claim 15 wherein said elongated body portion is a hollow conduit and means are disposed within the annular spaces between said tubular members and said conduit for placing said annular spaces in communication with said conduit.

18. A well tool as defined by claim 15 wherein said tubular members are perforated and said conduit is perforated over those portions of its length which extend between adjacent pairs of said retaining plates.

19. A well tool as defined by claim 15 wherein means for detecting physical conditions within the annular spaces between said tubular members and said body member are positioned within at least one of said annular spaces.

UNITED STATES PATENT OFFICE
Certificate of Correction

Patent No. 2,942,668

June 28, 1960

George P. Maly et al.

It is hereby certified that error appears in the above numbered patent requiring correction and that the said Letters Patent should read as corrected below.

In the drawings, Sheet 2, containing Figures 5 and 6, as shown below should be inserted as part of the Letters Patent:

in the heading to the present sheet of drawing, line 3, to the right of the filing date, insert —2 Sheets—Sheet 1—.
